US00D729788S

(12) **United States Design Patent**
Witter et al.

(10) **Patent No.:** **US D729,788 S**
(45) **Date of Patent:** **** May 19, 2015**

(54) **CASE FOR ELECTRONIC DEVICE**

- (71) Applicant: **OTTER PRODUCTS, LLC**, Fort Collins, CO (US)
- (72) Inventors: **Kevin W. Witter**, Fort Collins, CO (US); **Mark A. Giannasi**, Fort Collins, CO (US)
- (73) Assignee: **OTTER PRODUCTS, LLC**, Fort Collins, CO (US)
- (**) Term: **14 Years**
- (21) Appl. No.: **29/476,649**
- (22) Filed: **Dec. 16, 2013**
- (51) LOC (10) Cl. **14-03**
- (52) U.S. Cl. **USPC D14/250**

(57) **CLAIM**

The ornamental design for a case for electronic device, as shown and described.

DESCRIPTION

FIG. 1 is a first rear isometric view of a case for electronic device showing our new design;

FIG. 2 is a rear view thereof; and,

FIG. 3 is a second rear isometric view thereof.

In the drawings, the broken lines depict unclaimed environment and form no part of the claimed design.

1 Claim, 3 Drawing Sheets

FIG. 1

FIG. 2

FIG. 3
